UNITED STATES PATENT OFFICE.

SPENCER A. WELLS, OF SAN ANGELO, TEXAS.

MARKER.

1,192,719.

Specification of Letters Patent. Patented July 25, 1916.

Application filed September 2, 1914. Serial No. 859,844.

To all whom it may concern:

Be it known that I, SPENCER A. WELLS, a citizen of the United States, and a resident of San Angelo, in the county of Tom 5 Green and State of Texas, have invented a certain new and useful Improvement in Markers, adapted to be used in filing and card index cabinets, of which the following is a specification, reference being had to the 10 accompanying drawings.

The object of my invention is to provide a light, simply constructed V-shaped device, which can be readily inserted in the place from which certain correspondence or 15 a card has been removed, so that the exact location will be indicated from which the correspondence or card has been removed.

Another object is to provide a device of this general character, of a simple and inexpensive nature, and durable in construction, which shall be capable of convenient and accurate adjustment in position between certain correspondence or between index or like cards, to accurately indicate the place 25 from which certain papers or a card have been removed.

With these and other objects in view, the present invention consists in the combination and arrangement of parts as will be 30 hereinafter more fully described and finally pointed out in the appended claims, it being further understood that changes in the specific structure shown and described may be made within the scope of the claims without departing from the spirit of the invention.

In the accompanying drawings forming a part of this specification, and in which like numerals of reference indicate similar parts 40 in the several views: Figure 1 shows a vertical filing cabinet showing a marker embodying my invention in position to indicate the place from which certain papers have been removed. Fig. 2 is a perspective view of a marker embodying my invention. Fig. 3 shows a modification where I employ a pyramidal-shaped marker having a curved handle. Fig. 4 shows a modification in which the marker is provided with a knob. 45 Figs. 5 and 6 show wedge-shaped stub markers provided with gradually attenuated cylindrical stems.

In my present invention I provide a marker adapted to be used in designating 50 the place in a vertical filing cabinet or a card index system, where certain correspondence

or a certain card has been removed, so that the papers or card can later be readily replaced in proper position.

In the accompanying drawing A designates a cabinet, and B a drawer holding certain correspondence records *x*. In a space between portions of the correspondence records is shown a marker embodying my invention.

In its preferred form the marker includes a wedge-shaped member *a*, to the base *b* of which is secured a suitable wire handle *f*, this construction being shown in Fig. 2.

On removing certain correspondence from a filing cabinet when it is desired to indicate the exact location from which the correspondence has been removed, the operator simply introduces a wedge-shaped member *a*, in the place from which the correspondence has been removed. As a result, the adjacent papers are held in divergent spaced relation. When it is desired to replace the papers, the operator simply draws the wedge-shaped member toward the forward 80 end of the cabinet to provide a space to the rear of the marker into which the correspondence is inserted. The marker can then be retained in place or removed as desired.

If desired a pyramidal-shaped member 85 may be employed, as shown in Fig. 3 where a pyramidal-shaped member *c* is provided with the threaded opening 1 into which is screwed the end 2 of the curved stem *d*. This member is used exactly as is the wedge-shaped member.

In the modification shown in Fig. 4 the wedge-shaped member *a* is provided with a knob 3, instead of a wire handle *f*, as shown in Fig. 2. In the modification shown in 95 Figs. 5 and 6 stub wedge-shaped members *a* are shown being provided, respectively, with the gradually attenuated round straight stems 4 and 5. In these modifications a stub wedge instead of a long wedge is used, 100 as it is found that it is not necessary to have the wedge-shaped member *a* extend upward practically the full width of the correspondence, or the depth of the drawer.

It is of course understood that these 105 markers are made in different sizes, so as to be adapted to be used in connection with small filing card systems, as well as the conventionally used vertical filing cabinets.

The marker is simple and inexpensive in 110 construction, and both durable and efficient in operation, and can be adjusted between

a set of cards or between index or alphabetically arranged papers, so that any removed papers can be replaced with ease, accuracy and despatch.

5 Having thus described my said invention, what I claim as new and desire to secure by Letters Patent is:

1. A marker of the class described including a pyramidal-shaped member in combination with a curved handle.
- 10 2. A marker adapted to be placed in a

space between portions of correspondence, comprising a wedge-shaped member held base upward, and a handle secured to the base of said member.

15

In testimony whereof I affix my signature, in the presence of two witnesses.

SPENCER A. WELLS.
